UNITED STATES PATENT OFFICE

2,545,090

SHOE STRETCHER AND TREE

Michael F. Lau, Bridgeport, Conn.

Application August 18, 1949, Serial No. 110,970

1 Claim. (Cl. 12—128.4)

1

This invention relates to a combination shoe stretcher and tree and represents an improvement over the device shown and described in the Patent 1,700,724 issued to Frederick J. Lau, Sr., on January 29, 1924.

The primary object of the present invention is to provide a combination shoe stretcher and tree which is also exceedingly simple in structure and design and inexpensive, and which includes a means for exerting both a sidewise and upward stretching action on the vamp of the shoe. In the Patent 1,700,724, no means is provided for stretching the vamp upwardly as well as laterally.

Another important object of this invention is to provide a device of the character described in which the legs of a U-shaped spring wire are provided with opposed, offset arcuate portions which constitute the means for exerting a lateral or sidewise stretching action on the vamp, particularly adjacent the sole, which means is also an improvement over the simple curved end portions of the legs shown in the Patent 1,700,724.

These together with various ancillary objects and features of the invention which will later become apparent as the following description proceeds, are attained by the device, a preferred embodiment of which has been illustrated by way of example only in the accompanying drawings, wherein:

Figure 1 is a perspective view of the device shown applied in a shoe, the latter being shown in phantom;

Figure 2 is a top plan view of the device illustrating the spread apart position thereof;

Figure 3 is a top plan view of the device illustrating the manner in which the legs are urged together; and,

Figure 4 is a sectional view taken substantially on the plane of section line 4—4 of Figure 3.

Specific reference is now made to the drawings. In the several views in the accompanying drawings and in the following specification reference characters indicate corresponding elements throughout.

The device of the present invention is generally indicated at 10 and consists of a strand of spring material, such as resilient steel wire, bent over on itself intermediate its ends to a substantial U-formation including a bight portion 12 and leg portions 14 and 16. As will be readily understood by reference to Figure 2, the legs 14 and 16 are normally divergent or spread apart.

At their forward ends, the legs are bent to form opposing, offset laterally extending arcuate portions 18 and 20 which are adapted to engage the sides of the vamp 22 adjacent the sole 24 thereof as shown clearly in Figure 1.

The forwardmost ends of the arcuate portions 18 and 20 are further bent to form upwardly and rearwardly inclined rods 26 and 28, the free ends of which are outwardly curved or angulated as at 30 and 32. As will be seen clearly from Figure 1, the angulated or curved ends 30 and 32 of the

2

rods are adapted to engage the upper inner portion of the vamp to exert an upward stretching action thereagainst.

Slidably received on the legs 14 and 16 is a loop 34 which carries an elongated handle portion 36 having an eye 38 at the free end thereof, so that the eye can receive a nail, hook or any other pin in a supporting structure (not shown) for hanging the shoe stretcher so that the latter may in effect function as a tree.

In use, the loop 34 is slid on the legs 14 and 16 towards the arcuate, offset portions 18 and 20 to urge the legs together and assume the position shown in Figure 3. Thereafter, the stretcher is inserted within the shoe and the loop 34 is retracted on the legs 14 and 16 until the arcuate portions 18, 20, 30 and 32 engage and exert a stretching pressure on the inner surface of the vamp 22 as shown clearly in Figure 1. Thereafter, the stretcher and shoe may be suspended from the eye 38 carried by the loop.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A shoe stretcher and tree comprising a strand of substantially U-shaped spring wire having divergent legs, said legs including opposed laterally offset arcuate portions for engaging and exerting a sidewise stretching action on the vamp of a shoe, means for engaging and exerting an upward stretching action on the vamp of a shoe, said means including upwardly extending rods carried at the ends of the legs and inclined towards the web of said U-shaped spring wire, said rods including outwardly curved free ends, and a loop slidably on the legs for urging them together, said loop including a handle and an eye on the handle for hanging the same on a support.

MICHAEL F. LAU.
